ROCK AND ORE JAW CRUSHERS

Robert P. Fisher, Los Angeles, Calif.

Application December 18, 1952, Serial No. 326,624

2 Claims. (Cl. 241—262)

This invention relates to rock and ore jaw crushers, and more particularly to that type of crushers in which two crusher bodies or members are intermittently moved to and from each other in the crushing operation.

Among the salient objects of the present invention are:

To provide a crusher of the character referred to in which the two main body members or jaws have their crushing faces formed in successively offset steps or areas toward the top, with a detachable and replaceable crushing face member for each step or area, and in which the thickness of each face member corresponds substantially to the depth of the step or offset in the body or jaw member;

Another object of the invention is to provide two crushing body or jaw members, with the offset steps or areas and the replaceable face members, and which have slots or openings therethrough to the rear of the members for passage of fine material, dust and the like therethrough, to prevent accumulation and clogging of the machine in any way;

Another object of the invention is to provide in such a crusher a back or abutment member for each of the main jaw bodies, and which backing or abutment members have angular bearing faces, with means for adjusting them up and down, whereby such adjustment operates to move the regular jaw members to and from each other as said abutment members are adjusted, thus providing a simple means for adjusting the main jaw members to and from each other;

Another object of the invention is to provide an abutment member having inclined or angular abutment faces with ball bearings therein, whereby to greatly facilitate the adjustment movement, this being particularly advantageous in connection with the abutment member which is oscillated for the purpose of intermittently moving the jaw member in the crushing operation.

Other objects and advantages will be apparent from the following more detailed description of an embodiment of the invention, taken with the accompanying sheet of drawings, in which

Figure 1 is a vertical sectional view through a crusher embodying my invention;

Figure 2 is an end view of the machine, from the left hand end of Fig. 1;

Figure 3 is a fragmentary, enlarged view in section, to show the ball bearings on which the members move in connection with the crushing function; and

Figure 4 is a detail of one of the jaw face members, to show the slots or openings therethrough.

Referring now in detail to the drawings, the body of the crusher is composed of two side members, as 5, 5, with cross or connecting members, as 6, and with end members, as 7, 7, forming a rectangular body, open at the top and at the bottom.

In the right hand end of said body is an abutment member 8, having two inclined or angular abutment surfaces,

as 9, 9, with an opening 10 between said surfaces, as shown. This abutment member is provided with an arm 11 projecting out through an opening 12 in the end wall 7, as shown. An anchoring lug member 13 is shown 5 on the outside of said end member, with an adjustment screw 14 operating therethrough and connected with said arm 11, as shown, for the purpose of raising and lowering said abutment member 8, as will be understood from Fig. 1.

10 A jaw member 15 is shown having two inclined or angular surfaces in bearing with the surfaces 9, 9, of the member 8, as shown. A yielding tension rod 16 is connected at its inner end, as at 17, with said jaw member 15, and is extended out through the end wall member 7, and provided with a coiled spring 18, with a nut and washer, as at 19 for regulating the tension of the spring and the pull it exerts on the jaw member 15.

At the opposite end of said frame or body is a second abutment member 20, having two angular surfaces, as 21, 21, and an opening 22, between the inclined surfaces.

20 A second jaw member 23 is shown, corresponding to jaw member 15, has corresponding angular surfaces, as 24, 24 to cooperate with the surfaces 21, 21, as shown. This jaw member is mounted upon a ball bearing set at 25, to facilitate its movement toward and from the other jaw member 15, before mentioned. Said ball bearing member or assembly is shown in fragmentary sectional view in Fig. 3, with parts broken away, and is supported by a shaft or bar 26, having its opposite ends inserted 30 into the opposite jaw members 23, 23, as seen in Fig. 3, with a supporting bolt 27 from the middle thereof down to said ball bearing assembly. Said supporting bolt 27 passes through a slot in members 30 and 31, secured at their opposite ends to the side members 5, 5. The bar 26, secured at its opposite ends in the jaw member 23, and said bolt 27, and said ball bearing member 28, can move with said jaw members 23, 23 as they are moved slightly toward and from the other jaw member 15, in the crushing function. The lower edges or ends of said jaw members 23, 23 move on ball bearings, as at 23', 23'. Their movement is caused by the up and down movement of the movable abutment member 20, which is operated by the link 32, on an eccentric 33, on shaft 34, 40 driven by a pulley 35, with a belt 36 from any suitable power. The up and down movement is slight, and through the inclined or angular surfaces 21, 21, said jaw members 23 are moved toward and from the other jaw member 15 in a crushing action.

45 Ball bearing sets are shown in the inclined or angular surfaces, and these are designated 24', 24'. A bolt 37 has one end threaded into a connecting shaft 38 extended between the jaws 23, 23, and its other end is connected with a ball bearing set and provided with a nut 39. The 55 ball bearing set includes a plate 40, with a slot 40' for said bolt, and a plate 41 to which said bolt is connected and which moves with said bolt sufficiently to permit the slight up and down movement of the operating abutment members 20, from the eccentric 33.

Another bolt 42 has its threaded end in another cross shaft 43, connecting the two operating abutment members 20, 20, with its outer end connected through slot 44, in plate 45, and provided with a nut 46, securing it to an outer ball bearing plate 47.

60 The jaw members 15 and 23 have their adjacent faces formed with successive offset steps toward their upper ends, said offset steps being designated 15' and 23'. Each step or offset is provided with a jaw face member, as 48, having slots 49 therethrough and having teeth-like faces, as shown in enlarged view in Fig. 4. The slots 70 permit the dust and fine matter to work through and

drop down between the side jaw members 15, 15 and 23, 23.

Under the crusher jaws, I have shown an endless belt 50, running over a pulley 51, under the straight, parallel faces 52 and 53 of said jaws, for receiving and carrying the crushed material to any suitable place for discharge.

I do not limit the invention to the details of construction and arrangement here shown for explanatory purposes, except as I may be limited by the hereto appended claims forming a part of this specification.

I claim:

1. In a rock and ore crusher, the combination with an abutment member having inclined bearing surfaces and a jaw member having corresponding bearing surfaces, all of said bearing surfaces being parallel, bearing balls between said parallel bearing surfaces, and power means for moving said abutment member up and down for transmitting through said inclined bearing surfaces lateral crushing movement to said jaw member, of means for connecting said abutment member and said jaw member firmly together for relative sliding movement, said means comprising a bolt extending normal to said inclined bearing surfaces and having one end connected to said jaw member and its other end connected to said abutment member by means of a pair of plates extending parallel to all of said inclined bearing surfaces, and bearing balls interposed between said plates, said other end of the bolt being connected to one of said plates, the other plate

being carried by said abutment member and having a slot therein through which said bolt extends and is movable during relative sliding movement between said abutment member and said jaw member along their inclined bearing surfaces, and a horizontal ball bearing set beneath said jaw member for slidably supporting the latter in its said lateral movement.

2. A rock and ore crusher as defined in claim 1 in which said ball bearing set includes a pair of horizontal bearing members, bearing balls interposed between said bearing members, one of said bearing members having a slot extending in the direction of lateral movement of said jaw member, and a supporting bolt carried by said jaw member, said supporting bolt extending through said slot in said ore bearing member and being connected to the other bearing member.
